OIL BURNER

Walter C. Weaner, Muncie, Ind.

Application July 6, 1937, Serial No. 152,153

1 Claim. (Cl. 158—91)

This invention relates to improvements in heater devices wherein combustion is obtained from the mixture of air and the hydrocarbons derived from liquids such as fuel oil.

5 A device of the above description and which is commonly called an oil burner consists, broadly stated, of a metal bowl shaped combustion pot having a central dome provided with an oil orifice through which fuel oil is exuded, an inlet 10 pipe through which the fuel oil is fed to said orifice, an air intake manifold having its nozzle at position above the said dome, and where the air that is drawn through said manifold, is discharged, combustion taking place in the zone 15 above and about the said dome.

Objects of my invention are to provide improvements in a burner of the above description whereby the process of combustion is improved, noise is diminished, tendency of carbonization in 20 the fuel inlet pipe and orifice is prevented, facility for the dislodging of sediment in and about the orifice is afforded, and withal; whereby the burner lends itself readily to the use of control means that automatically cuts off the oil 25 supply at moments when predetermined levels are reached.

The aforesigned objects, as well as other and more specific aims of my invention are accomplished by, and the invention is embodied in the 30 new construction, combination and arrangement of parts described in the following specification, and illustrated in the accompanying drawing.

In the drawing—

Figure 1 is a top plan view of my improved oil 35 burner, portions of the air intake manifold being broken away.

Figure 2 is a vertical central sectional view taken on the line 2—2, and as seen in the direction of arrow 2 in Figure 1.

40 Figure 3 is a central vertical sectional view taken on the line 3—3, and as seen in the direction of arrow 3 in Figure 2.

Figure 4 is a top plan view of Figure 3, a portion of the combustion pot being broken away.

45 Figure 5 is an enlarged bottom plan view taken on the line 5—5, and as seen in the direction of arrow 5 in Figure 2, enlarged.

Figure 6 is a diagrammatic view showing a 50 typical installation wherein my improved oil burner is used.

In the typical embodiment of my invention as 55 it is illustrated herein, the structure is circular in plan formation, being about twelve inches in diameter and of capacity suitable for use in con-

ventional heater units such as stoves, furnaces and the like.

The substructure consists of a cast metal circular pan whose annular wall 1 is provided with rim 2 and annular seat 3. A central thimble 4 which is integrated with said sub-structure is of the height shown in Figure 2. Provided in the floor 5 is a regulating damper 6. Adapting the said pan for connections to suitable support means, are projections such as the bosses 7. 10

I provide a cast metal combustion pot which is of the formation in cross section as depicted in Figure 2, its central portion embodying a dome 10, and its flaring circular wall having the integrally formed downwardly directed annular 15 flange 11. The plane of the underside of the said flange is such, with relation to the plane of the annular seat 12 on the underside of the said dome, that when the combustion pot is placed in position, the said flange 11 and the said seat 12, 20 rest on the seat 3 of the pan, and on the rim of the thimble 4, respectively.

At the peak of said dome is an orifice 14 and with which communicates an oil feed pipe 15 which is screwed into position as shown in Figure 2. Spaced from and concentric with the said 25 orifice 14, is an annular race 16 and from which spiral channels 17 extend toward the base of the dome.

Provided in opposed incurved portions 20 of the 30 combustion pot, are circular openings 21 the planes of which are inclined toward the vertical axis of the dome. Each of said openings is provided with an arcuate flange 22 which constitutes a seat for the end of the air intake manifold 35 presently to be referred to. These said openings 21 are so located that the horizontal plane of their lower edges is a distance substantially above the plane of the peak of the dome, in the present instance, about three quarters of an inch. 40

Means for intake and draft of the air which enters the openings 21, consists of my improved manifold which is of the formation in plan, as shown in Figure 1, and in cross section, as shown in Figure 2. The similar tubular arms 24 and 24 45 whose outer ends rest on the flanges 22 and are seated in closed engagement with the openings 21, are in offset arrangement, the axis of each, at its inner end, being offset from the vertical axis of the said dome. Their proximate portions 50 merge and they constitute a hollow central body that embodies a downwardly directed nozzle 27 which discharges at the zone immediately above the aforesaid dome. At the underside of the roof of said hollow central body and at each side 55

of its vertical axis, is integrated a curved deflector 28. These deflectors are of contour to swerve the air currents as they move into the said hollow central body are so directed, that in 5 their passing from the nozzle, the vaporization of the gases present in the zone of the body portion of the combustion pot is facilitated, and at the same time there is absence of undue air pressure at the zone immediately adjacent the oil 10 orifice. The travel of the oppositely moving air currents being in paths offset from each other, clashing at the zone of the nozzle and where said air currents are discharged, is materially reduced, if not eliminated. Further contributing to the 15 shielding of the oil orifice from pressure tendency of the air being drawn down through the nozzle, is the cone shaped central deflector 30. This metal cone is integrated with a metal stem 31 which extends upwardly through a hole provided 20 therefor in the roof of the said manifold. Edged studs 32 which protrude from the bottom of said cone, rest in the annular race 16. The downwardly disposed stem 33 which is of tool steel and is fluted, is of diameter to be suitably received in 25 the bore of the oil feed pipe. Accordingly when the stem is rotated, as by applying a suitable implement, there is the dislodgement of deposit or sediment which may have formed in the bore of the pipe or in the race 16. Thus there is 30 facility for the conveniently cleaning of the oil orifice and the race, without the necessity of removing any of the parts of the device.

A burner device constructed in accordance with my invention is dependable in operation, easy to install, and is economical of manufacture.

Prepared for shipment and delivery to the user, it consists of the base pan, the combustion pot, which includes the stub length 15 of fuel feed pipe, the air intake manifold, and the central 40 deflector.

As illustrating the simplicity of installing, reference will be had to Figure 6 which is typical. After the base pan will have been disposed and made fast in the desired position on the grate bars of the furnace, and a packing of refractory material will have been provided thereat the combustion pot is disposed in place its annular flange or apron 11 resting within the rim 2 and upon the circular seat 3. The central deflector 45 is now put in place, the stem 33 being reposed in the bore of the pipe 15 and the studs 32 resting in the race 16. Now the air intake manifold unit is lowered to position its ends being reposed on the flanges 22 and embracing the openings 21, and the stem 31 of the deflector, protruding above 50 the said manifold.

The oil feed line having been connected by a suitable flexible pipe to the float control valve the latter is set at such position that its oil level 55 gauge line is coincident with the horizontal plane indicated by the dotted line in Figure 6, and which is about one quarter of an inch above the peak of the dome.

With the igniting of the oil and the warming 60 of the manifold there is the induction of draft and the incident vaporization of the hydro carbons. When the manifold will have become heated to operating temperature the constant draft will have become established.

65 The direction of the flow of the air currents into the air intake manifold openings 21 is indicated by the arrows in Figure 2. Unlike the burner devices embodying straight type air in-

take manifolds and wherein the air currents are in direct collision at the nozzle and vaporization is impeded; the flow of the air currents into and through the manifold and the nozzle of my improved construction is practically free; and moreover, the said air currents, as they enter the body portion of the manifold at the zone of the nozzle, are detoured by the deflector elements 28 and the cone 30. The zone immediately above the orifice being shielded by the cone there is the 10 steady and unimpeded yielding up of the exuding oil which flows from the race down the spiral channels 17. The distributed spread of fuel oil down the sloping surfaces of the zone yields up a uniformly distributed gas vapor which, caught 15 by the deflected air blast emanating from the nozzle, is effectively volatilized. The thimble 4 besides constituting a base upon which the combustion pot is partially supported, and whereby the dome portion of the pot is exposed to the outside 20 air, also constitutes a barrier to prevent the heat of the bottom or ring portion of the combustion pot from having effect upon the temperature of the fuel inlet pipe. This barrier being spaced from the said fuel inlet pipe, there is at all times 25 the presence of outside air about the pipe. The outside air within the confines of the thimble, assures the prevention of any overheating of the fuel inlet pipe, and it also negates any tendency 30 of the central portion of the dome structure of the pot to become overheated.

Through the combustion obtained by my invention, there is obtained the maximum of heat energy, with the expenditure of a minimum of fuel, and there is slight if any unconsumed gases.

In case of flame extinguishment the only effect is that the oil level rises to the dotted line (see Figure 6) at which moment the float control valve automatically operates thereby cutting off the oil supply. The air inlet openings 21 being 40 at a plane above the maximum oil level there is no liability of derangement of the device. Upon reigniting the oil, its level is soon lowered by its being consumed, to a level below the peak of the dome, after which the float control valve again 45 functions; this time to reestablish the feed of oil to the orifice.

Whereas I have shown and described what I consider a preferred embodiment of my invention, it will be understood that modifications may 50 be made as to formation and arrangement of the several parts, without departing from the spirit of the invention or sacrificing any of its advantages.

What I claim as my invention, is—

In an oil burner, a combustion pot having a concave bottom with a middle raised dome having a fuel orifice at its apex and having oblique manifold port seats in corresponding ports in two diametrically opposite walls, a manifold tube connecting the two seats and having downturned ends removably seated in the respective seats, and having an outlet port axially aligned with the axis of the fuel orifice in the dome, the manifold tube from each seat axially offset on opposite sides of the vertical axis of the fuel orifice, and a cone located above the dome having a stem from its apex seated in a hole in the top of the manifold tube and a ribbed stem from its base seated in the fuel orifice. 70
